UNITED STATES PATENT OFFICE.

SVEND HANSEN, OF BROOKLYN, NEW YORK, ASSIGNOR TO CAMERON MACHINE COMPANY, OF BROOKLYN, NEW YORK, A CORPORATION OF NEW YORK.

SLITTING AND REWINDING MACHINE.

1,257,853.

Specification of Letters Patent. Patented Feb. 26, 1918.

Application filed March 2, 1916. Serial No. 31,607.

To all whom it may concern:

Be it known that I, SVEND HANSEN, a citizen of the United States, and a resident of the borough of Brooklyn, city of New York, in the county of Kings and State of New York, have invented certain new and useful Improvements in Slitting and Rewinding Machines, of which the following is a specification.

10 The present invention relates generally, though not exclusively, to slitting and rewinding machines, and has more particularly reference to means for effectively separating side by side sections of flexible sheet material.

Certain materials, such as tinfoil, adhesive tape and other materials of a "tacky" or sticky nature when slit into sections have a tendency to reunite at the adjacent edges of the slit sections during rewinding on the same shaft or side by side. It has been attempted to overcome this defect by rewinding the sections on separate shafts, but this is disadvantageous because in that way the sections will be rewound into coils of varying diameters which consequently exert different pulls on different sections at the plane of severance with the result that the slitting is distorted and is not effected evenly. It is therefore preferable that the slit sections be rewound on the same shaft or side by side in order not to affect adversely the slitting operation. With this side by side rewinding construction attempts have been made to effect a physical separation of the slit sections by passing or guiding them through combs or a plurality of series of pins, transversely arranged in each series, and each series having the pins or combs spaced farther apart than the preceding comb or series of pins. While this effectually spreads the sections and physically separates them, it has a decided disadvantage in that the side edges of the sections are apt to be turned and folded back on themselves so that when rewound under pressure the turned-back edge becomes embedded in the coil. In slitting and rewinding tinfoil, for instance, the coil, owing to the heavy pressure exerted in rewinding, becomes practically a solid piece of metal in which the turned-back edge becomes embedded and from which it cannot be separated.

The main object of this invention is to spread slit sections of material without turning back the edges.

Other objects will appear as the specification proceeds.

One feature of the invention consists in bodily deflecting the slit sections into laterally spaced relation, as distinguished from deflecting the side edges of the material. This bodily deflection of the section is out of the plane of the web or out of the plane of severance and is effected with a progressively increasing pitch so as to laterally separate the sections. The slit sections which are thus bodily deflected are then brought back into one plane and rewound in lateral spaced relation side by side.

Another feature of the invention consists in a spacing or spreading device consisting of two straight rollers, and a member, composed of one or more parts, located intermediate the two straight rollers and having inclined surfaces of progressively increasing pitch laterally, together with means for guiding the sections over said rollers and member. Suitable means are also provided for holding the sections under tension. In the preferred form herein disclosed, this is effected by mounting the first straight roller rotatably and in providing means for retarding the rotation of the said roller, together with means for exerting a pull on the sections.

Preferably also the inclined surfaces are arranged in two series extending in opposite directions, each series having a progressively increasing pitch.

A still further feature of the invention resides in adapting this spreading or spacing device to a type of slitting machine embodying the "score-cut" method in which the cutting roller against which the cutters act also does duty as the second straight roller, the member with the inclined surfaces being located intermediate it and the first roller, and the web sections being led from the cutting roller to the first roller, then under the member with the inclined surfaces and then back to the upper part of the cutter roll. This cutter roll may, if desired, also form a part of the rewinding mechanism.

Other features of construction, combination of parts and arrangement of elements will appear as the specification proceeds.

In the accompanying drawings the invention is disclosed in several concrete and preferred forms, from which, however, changes may be made without departing from the legitimate and intended scope of the invention as expressed in the appended claims.

10 In the said drawings:

Figure 1 is a plan view of the rewinding mechanism of a rewinding and slitting machine embodying the invention, with parts removed and in section.

15 Fig. 2 is a vertical section on the line 2—2 of Fig. 1.

Fig. 3 is a vertical section on the line 3—3 of Fig. 1.

20 Fig. 4 is a diagrammatic plan view showing the path of the slitted sections.

Fig. 5 is a side elevation of a modified form of angle bar.

Fig. 6 is a view looking in the direction of the arrow 6 in Fig. 5.

25 Fig. 7 is a top plan view of Fig. 5.

Fig. 8 is a sectional view having a modified form of the invention.

Fig. 9 is a side elevation, partly in section, of a still further modified construction.

30 Fig. 10 is a view looking in the direction of the arrow 10 of Fig. 9.

Figs. 11 and 12 are detail views of the angle bars used in the modification shown in Figs. 9 and 10.

35 Similar characters of reference indicate corresponding parts in the several views.

1 indicates the cutter roll of a slitting and rewinding machine with which co-operates a plurality of cutting members, one of which 40 is shown at 2. 3 is a straight roller located in front of the cutter roll and rotatably mounted in the bracket 4. 5 is the spacing or spreading member located intermediate the cutter roll 1 and the roller 3. In the 45 embodiment of the invention shown in Figs. 1, 2, 3 and 4, the member 5 consists of a shaft 6 provided with a plurality of cone-shaped members 7 arranged in two series extending laterally in opposite directions 50 from the central member 7^a which is straight. The cone-shaped members have a progressively increasing pitch as best seen in Fig. 4, so that 7^a has a greater inclination than 7^b, and 7^c has a greater inclination than 7^d and so on. In the present instance, the members 7 are secured to the shaft 6 by means of screws 8 or otherwise. A brake band 9 is secured to the pin 10 on the bracket 4 and passes over the roller 3 60 and thence over the pin 11. The lower end of the brake band is weighted as at 12. The cutter roll 1 forms a part of the rewinding mechanism and together with the roller 13 and pressure roller 14 acts on the coils 15 on 65 the rewinding shaft 16 to rewind the slitted

sections, the members enumerated exerting a pull on said sections.

The web 17 is passed up between the roll 1 and cutters 2 where it is slitted into sections. These sections then pass to the roller 70 3 at the underside thereof, up around the same, thence to the underside of the member 5 and up over the cutter roll 1 to the rewinding shaft 16.

The sections in passing from roller 3 to 75

the cutter roll 1, under the member 5, are deflected bodily out of the plane of the web, without the necessity of engaging the side edges of the sections. Owing to the constant increase in pitch of the cones, the first 80

section, next to the middle section is deflected, say 1/64 inch, while the second section is deflected 2/64 inch and so on; each section being separated from its next preceding section. The sections in passing to the cutter roll 1 are then all brought back into one plane, but remain laterally separated and are then rewound side by side in laterally spaced relation. The brake band 9 serves to 85

retard the rotation of the roller 3 and prevents a slack from accumulating between the rollers 3 and 1 and the member 5, which slack would interfere with the control of the sections. It will be seen that the deflection 90

of the sections out of the plane of the web by the action of the member 5, amounts to a tilting, or rotating, of the sections about their longitudinal axes whereby the lateral edges of the sections are laterally deflected. The engagement of the tilted sections at a 95

later stage in their movement with the roller 1, produces a tilting of the sections in the reverse direction about one of the laterally deflected edges, with the consequent bodily lateral displacement of the sections as a 100 whole.

The bracket 4 is adjustably mounted on the studs 17, which latter are seated in the open bearings 18. By adjusting the studs 17 in said bearings 18, the member 5 may be 110 moved to the position found most advantageous in a given set of circumstances.

The cone-shaped members 7 may be provided with segments 19 constituting abutments to prevent undue slippage of the sections. The shaft 6 of the member 5 is adjustably mounted in the bracket 4 but is normally held in one position by means of the pull spring 20 secured to one end of the belt 21 passing over the pulley 22 on the end of 120 shaft 6. The other end of the belt 21 passes to the foot lever 23, the upward movement of which, under the influence of the spring 20, is limited by the stop 24. When threading the sections through the machine the 125 foot lever 23 may be depressed thereby imparting half a turn to the shaft 6 and bringing the segments 19 uppermost, thereby facilitating the threading operation. After the sections are threaded the lever 23 is re- 130

leased and the spring 20 restores the parts to their original position.

In the modification shown in Figs. 5, 6 and 7, the memb 5 consists of a number of straight cylinders 25, each adjustably mounted on a stem 26, which latter is extended into a socket 27 carried adjustably by a supporting member 28. By properly adjusting the stem 26 in the socket 27 or by adjusting the cylinder 25 on the stem 26, the proper degree of inclination can be given to the members 25 which then have the same action on the sections as the cone-shaped members.

15 In the modification shown in Fig. 8, the cone-shaped members 7 are rotatably mounted on the shaft 6. This form may be advantageous in handling unusually sticky material.

20 In Figs. 9 to 12 the general arrangement is the same as in Figs. 1 to 4. Here stationary brackets 29 carry the roller 3 rotatably mounted. Movable brackets 30 swing on the center 31 of the roller 3. Only 25 one stationary and one movable bracket is shown. The movable bracket 30 is normally held in the position shown in Fig. 9 by means of the cam 32, resting against the stop 33, under the action of the weight 34 secured to the movable brackets. By manipulating the handle 35 the movable bracket is given a turn around its center 31 and that portion thereof which is between the roller 3 and the cutter roll 1 can be elevated to facilitate threading or to obtain an adjustment.

Carried by the movable brackets 30 is a bar 36 on which are mounted a plurality of members 37 having inclined faces 38 (see Figs. 11 and 12). These members perform the same function as the members 7 in Figs. 1 to 4. The abutment members, here taking the form of guides 39 of sheet material, are mounted on arms 40 carried by the bar 41 on the movable brackets 30, and extend in between the members 37. Both the members 37 and the arms 40 are individually removable and adjustable by reason of set screws 42 and 43 and the open socket formations 44 and 45, so that the bars 36 and 41 need not be disturbed when removing or adjusting the parts.

What is claimed, is:

1. A slitting and rewinding machine comprising: means for slitting a web into sections, and means for bodily deflecting the slit sections out of the plane of the web with a progressively changing pitch and with substantially the same rate of change of pitch between sections to laterally separate the slit sections.

2. A slitting and rewinding machine comprising: means for angularly deflecting the slit sections about one edge as a pivot to laterally displace the other edge, means

for varying the deflection between sections at a progressively changing and substantially constant rate, and means for deflecting the sections about the other edge as a pivot and in the contrary direction whereby the sections as a whole will be laterally displaced.

3. A spacing device for strips of flexible sheet material comprising: means for moving and slitting a web into sections, guiding surfaces uncurved in lines transverse the sections for tilting each of the sections laterally to thereby laterally displace the edges thereof, and means for tilting the sections at a subsequent stage in their movement in a contrary direction about one of the displaced edges as a pivot, whereby the sections as a whole will be laterally displaced.

4. A spacing device for sections of flexible sheet material comprising: a guiding roller, a rewinding roller, a member, intermediate the two rollers, having inclined surfaces of progressively increasing pitch relative to each other, and means for guiding the sections from said guiding roller to said member and directly from said member to said rewinding roller.

5. A spacing device for sections of flexible sheet material comprising: a guiding roller, a rewinding roller, a member, intermediate the two rollers, having inclined surfaces of progressively increasing pitch laterally and relative to each other, means for guiding the sections from said guiding roller to said member and directly from said member to said rewinding roller, and means for holding the sections under tension.

6. A spacing device for sections of flexible sheet material comprising: a guiding roller rotatably mounted, a rewinding roller spaced therefrom, a member, intermediate the two rollers, having inclined surfaces of progressively increasing pitch relative to each other, means for guiding the sections over said rollers and member and directly from said member to said rewinding roller, means for exerting a pull on the sections, and means for retarding the rotation of the first roller.

7. A spacing device for sections of flexible sheet material comprising: a guiding roller, a rewinding roller, a member, intermediate the two rollers, having inclined surfaces of progressively increasing pitch relative to each other, said surfaces being arranged in two series extending in opposite directions laterally, and means for guiding the sections over said rollers and members.

8. A spacing device for sections of flexible sheet material comprising: a guiding roller, a rewinding roller, a member, intermediate the two rollers, having inclined surfaces of progressively increasing pitch relative to each other, said surfaces being arranged in

- two series extending in opposite directions laterally, means for guiding the sections over said rollers and members, and means for holding the sections under tension.
5. 9. A spacing device for sections of flexible sheet material comprising: a straight roller rotatably mounted, another straight roller spaced therefrom, a member, intermediate the two rollers, having inclined surfaces of progressively increasing pitch arranged in two series extending in opposite directions laterally, means for guiding the sections over said rollers and member, means for exerting a pull on the sections, and means for retarding the rotation of the first roller.
10. In a slitting and rewinding machine, a cutter roll, a cutting member engaging therewith, a straight roller located in front of the cutting roller and spaced therefrom, a member, intermediate the cutter roll and the straight roller, having inclined surfaces of progressively increasing pitch laterally, and a rewinding shaft, the slit sections being led from the cutter roll to the straight roller, thence to the intermediate member, then back to the cutter roll and thence to the rewinding shaft.
15. 11. In a slitting and rewinding machine, two straight rollers, and a spacing device intermediate the two rollers comprising: a bar, and a plurality of members, having inclined surfaces with relatively different inclinations, mounted on said bar and individually removable therefrom.
20. 12. In a slitting and rewinding machine, two straight rollers, and a spacing device intermediate the two rollers comprising: a bar, a plurality of members, having inclined surfaces with progressively differing inclinations, mounted on said bar and individually removable therefrom, and means for raising and lowering the bar between the two straight rollers.
25. 13. In a slitting and rewinding machine, two straight rollers, and a spacing device intermediate the two rollers comprising: a bar, a plurality of members, having inclined surfaces, mounted on said bar and individually removable therefrom, a swinging member supporting said bar, and means for effecting a movement of said swinging member to raise and lower the bar between the two straight rollers.
30. 14. In a slitting and rewinding machine, two straight rollers, and a spacing device intermediate the two rollers comprising: a bar, a plurality of members, having inclined surfaces, mounted on said bar, a second bar, and abutment members mounted on said second bar and extending in between the members on the first bar, and means for raising and lowering the bars between the straight rollers.
35. 15. In a slitting and rewinding machine, two straight rollers, and a spacing device intermediate the two rollers comprising: a bar, a plurality of members, having inclined surfaces, mounted on said bar, a second bar, abutment members mounted on said second bar and extending in between the members on the first bar, and means for raising and lowering the bars between the straight rollers.
40. 16. In a slitting and rewinding machine, two straight rollers, and a spacing device intermediate the two rollers comprising: a bar, a plurality of members, having inclined surfaces, mounted on said bar, a second bar, abutment members mounted on said second bar and extending in between the members on the first bar, a swinging member supporting said bars, and means for effecting a swinging movement of said swinging members to raise and lower the bars between the two straight rollers.
45. 17. In a slitting and rewinding machine, two straight rollers, and a spacing device intermediate the two rollers comprising: a bar, a plurality of deflecting members having relatively different deflecting positions mounted on said bar and removably secured thereto.

Signed at New York city, in the county of New York and State of New York, this 1st day of March, A. D. 1916.

SVEND HANSEN.
